[57] CLAIM

The ornamental design for an airless paint sprayer, as shown and described.

DESCRIPTION

FIG. 1 is a top plan view of an airless paint sprayer showing my new design;

FIG. 2 is a side elevational view thereof;

FIG. 3 is a front elevational view thereof;

FIG. 4 is an elevational view thereof as seen from the opposite side of FIG. 2;

FIG. 5 is a rear elevational view thereof; and

FIG. 6 is a perspective view thereof as seen from the top and front.

The broken lines of a hose are for illustrative purposes only and form no part of the claimed design.
